Inventor

Adam Scott,

UNITED STATES PATENT OFFICE.

ADAM SCOTT, OF WILMINGTON, OHIO.

DESIGN FOR A COLLAR-PAD.

SPECIFICATION forming part of Design No. 20,919, dated July 7, 1891.

Application filed December 23, 1890. Serial No. 375,619. Term of patent 14 years.

To all whom it may concern:

Be it known that I, ADAM SCOTT, a citizen of the United States, residing at Wilmington, in the county of Clinton and State of Ohio, have invented a new and original Design for a Combined Sweat and Collar Pad, of which the following is a specification.

My design for a sweat and collar pad is fully illustrated in the accompanying drawings, in which Figure 1 is a perspective view of the same, and Fig. 2 is a plan view flattened.

The main feature of my design consists in the contour of the pad, which has its outline substantially of a conventional bow shape, the center of the pad being enlarged and having a perforation within the enlarged portion.

In the drawings, the letter A designates my pad, which has its forward outline a of the general shape of a conventional bow, and also

has its rear outline a' of a similar shape. The forward and rear outlines a and a' are joined at their extremities by the curved lines a^2 . At the center of the pad the same is enlarged, as shown at A' , and within this enlarged portion is a perforation a^3 .

I claim—

The design for a collar and sweat pad herein shown and described, the same consisting of a pad provided with longitudinal convex ribs and having its longitudinal edges concavely and convexly curved or scalloped and provided with a central circular enlargement having a central opening, as set forth. 35

In testimony that I claim the foregoing as my own I have hereto affixed my signature in presence of two witnesses.

ADAM SCOTT.

Witnesses:

C. H. HUNT,
KENT P. BROWNING.
